INVENTOR.

UNITED STATES PATENT OFFICE.

FREDERICK C. GUERRLICH, OF STAMFORD, CONNECTICUT.

INTERNAL-COMBUSTION ENGINE.

1,346,123.

Specification of Letters Patent. Patented July 13, 1920.

Application filed May 17, 1918. Serial No. 235,148.

To all whom it may concern:

Be it known that I, FREDERICK C. GUERRLICH, a citizen of the United States, and a resident of Stamford, in the county of Fairfield and State of Connecticut, have invented certain new and useful Improvements in Internal-Combustion Engines, of which the following is a specification.

This invention relates generally to improvements in internal combustion engines. The invention finds one advantageous use in aeronautic engines in that means are provided which render the internal combustion engine more reliable and satisfactory for aeronautic service. The invention is, however, capable of other and advantageous uses, as will later appear.

It is well known that aeroplane engines are subject to serious difficulties which are caused by the variations in atmospheric pressure encountered while the aeroplane is in flight. The high altitudes attained and the rapid transitions from high to lower altitudes cause large and at times rapid variations in the pressure and density of the air supplied to the engine. Not only do these barometric changes cause irregularity in the running of the engine, but there is a serious loss of power when the aeroplane is in the higher altitudes, due to the lowered degrees of compression and the fact that decreased weights of fuel mixture are supplied to the engine. This invention is concerned, among other things, with the elimination of the difficulties heretofore encountered in aeronautic motors.

The invention has for its broad object to provide means whereby the air and fuel supplied to an internal combustion engine may be maintained constant at any desired predetermined pressure and density, irrespective of variations in atmospheric pressure.

Another object of the invention is to provide in combination with an internal combustion engine and adequate mechanical pumping means to deliver air to the carbureter of the engine, a relief valve to maintain the pressure and density of the pumped air constant, the valve being characterized in that entrapped air is utilized as the force to hold the valve in closed position and in that variations in atmospheric conditions are prevented from affecting the operation of the valve.

Another object of the invention is the

provision of power-operated pumping means in combination with the engine and its carbureter for the purpose of increasing the power obtainable from the engine without varying its dimensions.

Other objects and advantages will appear in the following description and in the illustrative embodiment of the invention in the accompanying drawings, in which:

Figure 1 is an elevational view, partly in section, of an internal combustion engine embodying the invention;

Fig. 2 is a cross-sectional view taken on the line 2—2 of Fig. 1;

Fig. 3 is an enlarged sectional view of the pressure regulator shown in Fig. 1;

Fig. 4 is a fragmentary sectional view showing a modification of the regulator; and

Fig. 5 is a fragmentary sectional view showing a further modification of the regulator.

Referring to these drawings in detail and particularly to Figs. 1 and 2: A represents an internal combustion engine of any suitable type, and the invention is, in the main, independent of the particular constructional details of the parts of engine A. It will therefore suffice to state that the cylinders, pistons, piston rods, crankshaft and crank case of the engine are represented in illustrative form by reference letters b, c, d, e and f, respectively. The intake manifold of the engine is indicated at g, and h is a suitable carbureter connected to manifold g. Carbureter h is supplied with fuel by suitable means (not shown) through an inlet pipe i, preferably fitted with a non-return valve k, and with air by means of an inlet pipe j.

According to my invention, I provide an air-tight inclosure for the carbureter, h, as a casing 6, and all the parts which pass through the casing are arranged so as to prevent the inflow or outflow of air to or from the latter. Thus, pipe i and the operating rod j' of the carbureter throttle valve enter the casing through suitable stuffing-boxes 7 and 8, respectively, and the joint between the intake manifold g and casing 6 may be sealed by a gasket 9. In order to supply air to the intake j, a pipe 10 is connected at one end to casing 6 and at the other end to suitable mechanical pumping means. Obviously, such means may be of any desired type, and, merely by way of

illustrative example, the engine itself has been utilized as the pumping means, the pistons being arranged to coöperate with the crank case for this purpose. Thus, the 5 crank case *f* is divided by partitions *k*, into a plurality of compartments *l*, one for each cylinder *b* of the engine, to form pump cylinders. Each compartment *l* is provided with an air intake valve, conventionally indicated at 11 (Fig. 2), which valve opens by suction on the upstroke of piston *c* to admit air into the compartment. The pipe 10, described, is connected, as indicated in Figs. 1 and 2, to each of the compartments *l*, and 10 in each of the connections is an outwardly-opening non-return valve, conventionally indicated at 12. It will thus be seen that on the down-stroke of each piston, air, taken into compartments *l* on the up-stroke of 15 the pistons, will be compressed and delivered through pipe 10 to the casing 6 and thus to carbureter *h*. Obviously, the capacity of the pumping means described may readily be made anything desired by variation of the proportions illustrated.

It is desired to maintain the air in casing 6 at a constant predetermined pressure and density, irrespective of pressure variations outside the casing. To accomplish this result, a pressure regulator *B* is associated with pipe 10 as indicated in Fig. 1. The regulator is best shown in, and will be described in connection with, its separate illustration in Fig. 3. The regulator *B* is 20 provided with two spaced compartments 13 and 14, the former being always in communication with pipe 10, as shown. Intermediate the chambers 13 and 14 is a chamber 15 which communicates at all times 25 with the atmosphere by one or more ports 16 and which may communicate with chamber 13 upon the opening of a valve 17. The stem of valve 17 enters into compartment 14 and the latter constitutes a cylinder in which 30 a piston 18 on the stem of valve 17 may move. The piston 18 is arranged to be acted upon by a constant pressure to hold valve 17 in the closed position illustrated.

Preferably, this constant pressure is obtained by a body of air entrapped in the 35 upper portion of a chamber 19 which at all times communicates with chamber 14. The lower parts of chambers 14 and 19 may, as illustrated, receive a body of oil or the like, 40 the arrangement being such that the oil acts as a transmitting medium between the entrapped body of air and piston 18 and functions as an oil seal to prevent the escape of the entrapped air past the piston. While 45 the oil seal is desirable, it is not absolutely essential and is illustrated merely as a simple means for preventing the escape of the entrapped air. Chamber 19 is provided with a pet-cock 20 which is normally closed 50 and is provided solely for the purpose of

admitting air to the chamber, as will later appear.

It is particularly to be noted that the adjacent faces of valve 17 and piston 18 are both exposed to atmospheric pressure, and 55 in order to remove atmospheric pressure as a factor in the operation of the pressure regulator, the area of the under face of valve 17 is made equal to that of the upper face of piston 18. Thus, atmospheric pressure acts equally on valve 17 and piston 18 and in opposite directions, so that the resultant effect is zero. The area of the upper face of valve 17 relative to the area of the lower face of piston 18 is not important 60 as it has no effect upon the maintenance of a constant pressure in pipe 10. It is desirable, however, that the effective area of the valve 17 should be, as nearly as possible, equal to the lower face of piston 18, if it is desired to 65 maintain the pressure in pipe 10 constant at substantially normal atmospheric pressure, for the chamber 19 is supplied, as will appear, with air at substantially normal atmospheric pressure.

The operation of the pressure regulator will now be described. The pet-cock 20 is opened while valve 17 is held in closed position, whereby air may be admitted into the upper part of chamber 19. After the pet-cock 20 has been closed, it will be apparent that valve 17 will open as soon as the pressure in pipe 10 exceeds a predetermined value, which is substantially that existing 70 in chamber 19, but not exactly in the illustrated embodiment of the invention due to the slight difference in area between the effective top face of valve 17 and the bottom face of the piston 18. The valve is opened by the moving force of the pressure 75 in the inclosure 6 when it is greater than the pressure of the moving force in the chamber 19, and closed by the moving force of the pressure in the chamber 19 when it is 80 the greater.

Obviously, the valve may be made to open at any other predetermined pressure, as desired. For example, the pressure at which valve 17 will open may be increased in many ways, as for example, by inserting a spring 85 21 between the lower face of valve 17 and the spider 22, which guides the stem of valve 17, as clearly shown in Fig. 4. Obviously, the pressure at which valve 17 will open may be also increased by admitting compressed 90 air into chamber 19, and similarly, if it is desired to have valve 17 open at less than atmospheric pressure, a partial vacuum may be created in chamber 19. A spring, as 95 in Fig. 5, may be arranged to hold valve 17 in closed position, but unless such spring is arranged in an absolute vacuum, there is still entrapped air operating in addition to the spring to hold valve 17 in closed position. In the event of an absolute vacuum, which 100

can hardly be obtained, it is considered that this is merely a special case where the pressure of the entrapped air is zero. Although I may most conveniently cause valve 17 to 5 open at substantially the sea level pressure of the atmosphere, I do not wish to limit myself to such pressure, as, obviously, other pressures may be readily used as desired, and the essential is that the valve 17 may be 10 made to open at a constant pressure irrespective of variations in atmospheric pressure so as to connect the interior of the chamber with the external air of lower density and permit the air within the chamber to escape 15 so as to maintain the internal density substantially constant.

The regulator finds one advantageous use in connection with aeronautic engines. Thus, the aviator may fill chamber 19, as 20 described, when the aeroplane is on the ground. Thereafter he can rest assured that the air, as well as the fuel, supplied to his engine will be kept under substantially the same pressure and density conditions as exist at sea level, irrespective of the variations 25 in atmospheric pressure which obtain while the aeroplane is in flight.

An important feature of the regulator consists in the arrangement whereby 30 trapped air is utilized as a force to hold the valve 17 in closed position. The entrapped air functions like a spring to yieldingly hold the valve in closed position and has the advantage of being a simple but accurate 35 means to obtain the desired pressure (usually the sea level pressure of the atmosphere) on the valve. Furthermore, the regulator may readily be made to open at other than the sea level pressure of the atmosphere by 40 simply admitting air at the desired pressure to chamber 19. The use of entrapped air as the force to yieldingly hold the valve in closed position has therefore an advantage over a spring in that the action of a 45 relief valve held closed by a spring alone would be affected by variations in atmospheric pressure.

The invention is, however, capable of other and advantageous uses. For example, 50 the compression of the air prior to its delivery to the carburetor necessarily results in heating the air, and the heat imparted may be varied according to the degree of compression, which, as has been shown, may 55 be made of any degree desired. The useful effect of heating the air prior to delivery to the carburetor, acts, as is well known, to facilitate vaporization of the fuel. This desirable result is obtained in a different manner 60 than heretofore and in a manner which is particularly desirable since other advantageous results are coupled with it.

Some of such useful results have been already pointed out. It has been shown that 65 the compressor and its pressure regulator

may be arranged to supply air at a pressure greater than that of the atmosphere. Thus, is afforded a means for charging the engine with a fuel mixture at increased pressures, which necessarily results in increased power 70 from an engine of given dimensions, since increased weights of fuel may be drawn in and increased compression of fuel obtained. The air before being taken into the engine may be cooled by any suitable means, and 75 in the present embodiment of the invention it is cooled to a degree by the vaporization of the fuel, so that the heat due to compression by the pumping means is converted into heat for vaporization with obviously useful 80 results.

Thus, I have provided in an internal combustion engine a means for maintaining the constituents of the fuel mixture at a constant pressure and density irrespective of 85 barometric variations and a means whereby the pressure can be conveniently maintained constant at substantially the pressure of the atmosphere at sea level, or any other desired pressure.

The invention has been described herein in one embodiment for illustrative purposes, but the scope of the invention is defined by the appended claims rather than by the foregoing description.

What I claim is:

1. An inclosure containing air tending to vary in density, in combination with density controlling means normally exposed to the external atmosphere and tending to act to 100 reduce the density of said air when said density becomes greater than a predetermined density, and means for preventing said density controlling means from being substantially affected by variations in atmospheric pressure.

2. An inclosure containing air tending to vary in density, means for supplying air under pressure thereto, a valve for controlling the density of the air in said inclosure, 110 a second inclosure containing entrapped air and having a movable wall mechanically connected to said valve and acting to control the opening and closing of said valve so as to confine the variation in the density 115 of said air to narrow limits independently of variations in atmospheric pressure.

3. An inclosure containing air tending to vary in density and having a port adapted to connect the air within said inclosure with external air, a valve controlling said port, and means for controlling the opening and closing of said valve, said means comprising a chamber containing entrapped air at a predetermined pressure and having a movable wall mechanically connected to said valve.

4. An inclosure containing air tending to vary in density and having a port adapted to connect the air within said inclosure with

- external air of lower density, a valve for controlling said port exposed to said external air, means for controlling the opening and closing of said valve, said means comprising a chamber containing entrapped air at a predetermined pressure and having a movable wall connected to said valve, and means for supplying air under pressure to said inclosure independently of said port.
10. 5. An inclosure containing air tending to vary in density and having a port adapted to connect the interior of said inclosure with external air of lower density, an outwardly opening valve normally closing said port and tending to open when the density within said inclosure exceeds a predetermined amount, and means for closing said valve comprising a chamber containing entrapped air at a predetermined pressure and having a movable wall mechanically connected to said valve, the movement of said wall being determined by the variations in density in said inclosure, and means for supplying air under pressure to said inclosure independently of said port.
6. The combination of an inclosure for supplying air to an internal combustion engine and having a port opening to external air of lower density, a second inclosure containing an entrapped gaseous body, and a valve for said support whose movements are controlled by the resultant of the actions of the gaseous pressures within said two inclosures.
35. 7. The combination of an inclosure for supplying air to an internal combustion engine, a second inclosure containing an entrapped gaseous body, a relief valve for said first inclosure, whose operation is controlled by the resultant of the actions of the gaseous pressures within said two inclosures.
8. Controlling means for an inclosure supplied with air, comprising a valve opening to external air of lower density, a separate inclosure containing an entrapped gaseous body and having a movable portion mechanically connected to said valve and actuated by the moving force of air pressure within said first inclosure and the moving force of the pressure of said gaseous body, said forces being exerted in opposite directions parallel with the line of movement of said portion.
55. 9. Controlling means for an inclosure supplied with air comprising a valve seat and valve for said inclosure, a separate inclosure containing a confined gaseous body and a movable member connected to said valve and actuated by the moving force of pressure of the air within said first inclosure and the moving force of pressure of said gaseous body, said forces being exerted in opposite directions, said second inclosure having a portion in the form of a cylinder and said member having a portion in the form of a piston fitting therein, and a liquid seal between said piston and said confined gaseous body.
10. Controlling means for an inclosure supplied with air comprising a valve seat and valve for said inclosure, a separate inclosure containing a confined gaseous body and a movable member connected to said valve and actuated by the moving force of pressure of the air within said first inclosure and the moving force of pressure of said gaseous body, said forces being exerted on said member in opposite directions parallel with the line of movement of said member, said valve and said member having a common axis and moving in a direction parallel to said axis.
11. Controlling means for an inclosure supplied with air comprising a valve seat and valve for said inclosure, a separate inclosure containing a confined gaseous body and a movable member connected to said valve and actuated by the moving force of pressure of the air within said first inclosure and the moving force of pressure of said gaseous body, said pressures resulting in said forces being exerted on said member in opposite directions parallel with the line of movement of said member, the surfaces of said member subject to said opposing pressures being approximately equal in area.
12. The combination with an internal combustion engine, of a power-operated compressor arranged to produce pressure of the air at the air inlet, controlling means exposed to atmospheric pressure to maintain such air at a predetermined pressure for a given atmospheric pressure, and means for preventing variations in the pressure of the atmosphere from affecting said controlling means and the air supplied to said engine.
13. Means for supplying air at approximately constant pressure to internal combustion engines at varying altitudes, comprising the combination of an inclosure for air whose pressure tends to vary, power-operated means for supplying air thereto, a relief valve for said inclosure, adapted to connect the interior of said first inclosure with the atmosphere, means for exerting a closing force on said relief valve at a predetermined atmospheric pressure, and means for automatically varying the valve closing force inversely as the atmospheric pressure varies.
14. A relief valve, comprising a casing having a passage for connection to a supply pipe, a chamber at all times communicating with the atmosphere and a cylinder one end of which communicates with said chamber, a valve operable to connect said passage and chamber when the pressure in said pipe exceeds a predetermined value, and a piston in said cylinder connected to said valve, said cylinder adapted to receive an entrapped

gaseous body to support said piston and yieldingly hold said valve in closed position.

15. A relief valve, comprising a casing having a passage for connection to a supply pipe, a chamber at all times communicating with the atmosphere and a cylinder one end of which communicates with said chamber, a valve operable to connect said passage and chamber when the pressure in 10 said pipe exceeds a predetermined value, and a piston in said cylinder connected to

said valve, said cylinder adapted to receive an entrapped gaseous body to support said piston and yieldingly hold said valve in closed position, the adjacent faces of said 15 valve and piston being equal in area, whereby the effect of atmospheric pressure on the relief valve is neutralized.

FREDERICK C. GUERRLICH.
